UNITED STATES PATENT OFFICE

2,564,314

PEN NIB

Edward Sokolik, New Brighton, Minn.

Application May 29, 1947, Serial No. 751,342

1 Claim. (Cl. 120—109)

1

My present invention relates to improvements in pen nibs and the object is to provide a pen nib whose writing life is greatly prolonged and the performance in writing improved.

I attain these and other advantages, as will be apparent in the following specifications, by a novel construction of the writing end-portion of the pen nib.

In the drawing:

The figure in the drawing is a plan view of the convex side of my improved pen nib.

The pen nib, as illustrated by Fig. 1, comprises a conventionally concave body-portion A, which includes a main body-portion 2 and a writing end-portion 3. The design of the main body-portion 2 is largely a matter of choice and the design of the writing end-portion 3, is where the novelty resides, and consists of a tongue 4 and a pair of writing nibs 5 and 6, all extending from a common transverse juncture line 7 from the main body-portion 2.

The tongue 4 extends centrally from the main body-portion 2, and the writing nibs 5 and 6 extend downwardly along the edges 8 of the tongue 4 and beyond the point 9 thereof.

The nibs 5 and 6 have, each, an outer edge 10, of which, the upper portion 11, is a rectilinear extension of the edge 12 of the main body-portion 2, and the lower portion 13, which is slightly arcuate, converges with the corresponding lower portion 13 of the opposite nib to form a conventionally common writing point 14, and is substantially two and one-half times the length of the upper edge portion 11 of the edge 10.

The tongue 4 and nibs 5 and 6 are delineated by a slit 15 extending centrally between the nibs 5 and 6 from the common writing point 14 thereof to a point 16, which is a rectilinear distance from the common writing point 14 thereof, and from the junctures 17 of the upper portions 11 and the lower portion 13 of the outer edges 10, substantially in proportions of 5 parts to eight parts, respectively.

Branching and diverging from the upper end of the slit 15, as indicated at 18, are slits 18, each arcuately contoured to the arcuate lower edge portion 13 of each outer edge 10, and slightly diverging therefrom as each slit 18 progresses to a climax point, each of which points 19, is a minimum distance from each juncture 17 of the upper edge portion 11 and the lower edge portion 13 of each outer edge 10. From each turning point 19, each slit 18 has an extension slit 20 slightly converging at an angle substantially corresponding in degrees to the diverging angles of the branch slit 18 to the common juncture line 7 at which the nibs 5 and 6 and the tongue 4, are preferably of equal widths.

The nibs 5 and 6 gradually increase in width from the writing point 14 to the transverse common juncture line 7. The slit portions 20 facilitate springing of the nibs 5 and 6 and consequently

greatly prolong the springing life of the nibs 5 and 6. As illustrated, there is no conventional aperture in the nibs 5 and 6 at the point 16, whereby the nibs would be weakened at that point.

What I claim is:

A pen nib comprising, a main body portion, a writing end-portion which includes a tongue and a pair of nibs all having a transversely integral juncture with the main body portion on a common line, each writing nib extending downwardly adjoining the edge of the tongue and beyond the free point of the tongue, and each including an outer edge, the upper portion of which is a rectilinear extension of each edge of the main body portion and the lower portion of which is slightly arcuate and converges with the corresponding lower portion of the outer edge of the opposite nib to form a common writing point, the arcuate lower portion of each outer edge being substantially two and one-half times the length of the rectilinear extension of each edge of the main body portion, said tongue and nibs being delineated by a slit extending centrally between the nibs from the common writing point thereof to a point which is a rectilinear distance from the common writing point and from the junctures of the lower and upper portions of the outer edges, substantially in proportions of five parts to eight parts respectively, thence branching and diverging, each branch slit extending, arcuately contoured to the arcuate edge of the lower portion of the outer edge of each nib and slightly diverged therefrom, to a climax point, each of which is a substantially minimum distance from the juncture of the upper and lower portions of each outer edge, and from which, the branch slits are extended, at slightly converging angles, substantially corresponding in degrees to the degrees of the diverging angles of the branch slits, to the common juncture line with the main body portion, where each nib and the tongue are substantially of equal widths, such construction prolonging the springing life of the writing nibs.

EDWARD SOKOLIK.
